MINING MACHINE

Morris P. Holmes, Claremont, N. H., assignor to
 Sullivan Machinery Company, a corporation of
 Massachusetts

Application June 9, 1931, Serial No. 543,146

61 Claims. (Cl. 262—30)

This invention relates to mining machines, and more particularly to improvements in coal mining machines of the flexibly fed, continuous cutter type having improved adjustable kerf cutting mechanism.

An object of this invention is to provide an improved coal mining machine. Another object is to provide an improved coal mining machine of the flexibly fed, continuous cutter type having improved adjustable kerf cutting mechanism whereby the kerf cutter may be positioned into different elevated positions. A further object is to provide an improved coal mining machine of the flexibly fed, longwall type having improved means for adjusting the kerf cutter into different elevated positions and for swinging the kerf cutter about its pivot. A further object is to provide an improved longwall coal mining machine of the flexibly fed type having improved power operated means for swinging the kerf cutter about its pivot wherein the kerf cutter swinging means is operable entirely independently of the machine feeding means. Still another object is to provide an improved adjustable cutter head for a longwall coal mining machine. Yet another object is to provide an improved coal mining machine of the overcutting, longwall type wherein the kerf cutter is positionable to cut kerfs at different elevations above the mine floor. These and other objects and advantages of the invention will, however, hereinafter more fully appear.

In the accompanying drawings there is shown for purposes of illustration one form which the invention may assume in practice.

In these drawings,—

Fig. 1 is a plan view of the illustrative embodiment of the improved coal mining machine.

Fig. 2 is a side elevational view of the machine shown in Fig. 1.

Fig. 3 is a longitudinally extending vertical sectional view taken substantially on line 3—3 of Figs. 1 and 4.

Fig. 4 is a horizontal sectional view taken substantially on line 4—4 of Figs. 2 and 3.

Fig. 5 is a developed vertical sectional view taken substantially on line 5—5 of Fig. 4.

Fig. 6 is a detail view illustrating the improved clutch controlling means.

In this illustrative embodiment of the invention there is shown a coal mining machine of the flexibly fed, continuous cutter, longwall type generally comprising a frame 7 having a plane bottom surface 8 for slidably supporting the machine on the mine floor. Pivotal mounted

at 9 on the machine frame for swinging movement in a horizontal direction is a kerf cutter 10 mounted in an improved manner on adjustable supporting means, generally designated 11. The machine is fed over the mine floor at a high machine moving speed and at a relatively slow cutting speed by flexible feeding means including a feed drum 12 journaled on the forward end of the machine frame for rotation about a vertical axis, and a feed cable or rope 13 is wound upon this drum. Horizontal guide rolls 14 are arranged at the opposite front corners of the machine frame, and these rolls are adapted to guide the feed cable during the various operations of the machine. During feeding the free end of the feed cable is connectible in a well known manner to an anchor arranged adjacent the coal face in advance of the machine. As the feed cable 13 is drawn in by the feed drum 12, the mining machine is fed bodily over the mine floor. Arranged within the machine frame is a horizontal motor 15, herein preferably of the reversible electric type; having its power shaft horizontally disposed and extending longitudinally of the machine, and the forward end of the motor power shaft is operatively connected to the feed drum 12 through a plural speed transmission mechanism of the same general character as that described in my copending application Ser. No. 136,446, filed Sept. 20, 1926, now matured into Patent No. 1,815,872, patented July 21, 1931.

Now referring to the improved adjustable kerf cutting mechanism, it will be noted that keyed to the rear end of the motor power shaft, as shown in Fig. 3, is a bevel pinion 16 meshing with a horizontal bevel gear 17, keyed to a vertical shaft 18 and suitably journaled in the cutter frame section 19. Rotatable with and driven by the bevel gear 17 is a spur pinion 20 meshing with a large spur gear 21 keyed at 22 to a clutch sleeve 23 rotatably mounted on a vertical shaft 24. This shaft is suitably journaled within the cutter frame section 19 and has formed thereon clutch teeth 25 connectible by a sliding clutch member 26 to clutch teeth 27 formed on the clutch sleeve 23. It will thus be seen that when the clutch 26 is in its connected position and the clutch teeth 25, 27 are connected together, the shaft 24 may be driven by the gear 21 through the bevel gearing 16, 17 and spur pinion 20. Mounted on the cutter frame section 19 for adjustment in a vertical direction relative thereto in an improved manner to be hereinafter described is a frame 28 having secured thereto a central bearing support 29 car-

50

55

rying bearings within which a hollow shaft 30 is journaled, the shaft 30 being arranged with its axis alined with that of shaft 24, which is likewise made hollow. Mounted within the shaft 30 is a shaft 31, in this instance, telescopically arranged within the hollow shaft 24 and to which the latter is splined at 32. The elements 24 and 31 cooperate to provide an extensible driving connection in the form of a telescopic torque shaft 10 between the driving element on the frame and the driven element on the adjustable support and the splined shaft 31 is adjustable in a vertical direction relative to the shaft 24 and is driven by the shaft 24 through the splined connection 32, and keyed to the upper end of the shaft 31 is a sprocket 33 which engages and drives a cutter bit carrying cutter chain 34 mounted on the margin of an elongated plane cutter bar 35 for circulation thereabout, the cutter chain and cutter bar constituting the kerf cutter 10. As shown in Fig. 3, the cutter bar 35 is secured by bolts 36 to an annular frame member or swivel frame 37 having a radial flange 38 rotatably mounted between spaced bearing rings 39. The bearing rings are suitably supported within the adjustable frame member 28 and are retained in position by an annular ring member 40 bolted to the frame 28 in the manner shown. It will thus be seen that the members 37, 39 form a swivel mounting for the kerf cutter on which the latter is mounted for swinging movement about the axis of the vertical shaft 31.

The improved means for swinging the kerf cutter about its pivot herein comprises a spur gear 41 rotatable with and driven by the spur gear 21, and meshing with the spur gear 41 are spur gears 42 and 43 keyed to the lower ends of parallel vertical shafts 44 and 45 respectively arranged at opposite sides of the longitudinal vertical center of the machine as shown in Figs. 4 and 5. Herein fixed to the parallel shafts 44 and 45 are worms 46 and 47 having teeth of the same pitch but of opposite inclination and respectively meshing with worm wheels 48 and 49. The worm wheel 48 is connectible by a multiple disc clutch 50 to a horizontal shaft 51 arranged transversely of the cutter frame section 19 and suitably journaled therein. The worm wheel 49 is connectible to the shaft 51 by a multiple disc clutch 52. Fixed 50 to the shaft 51 and driven thereby is a worm 53 meshing with a horizontal worm wheel 54 having its hub suitably journaled within bearing sleeves 55 carried within the cutter frame section. The hub of this worm wheel is splined at 56 to a vertical shaft 57 and the shaft 57 extends through the hub of the worm wheel and is driven by the worm wheel through the splined connection 56. The worm wheel hub and the shaft 57 cooperate to provide an extensible driving connection in the form of a telescopic torque shaft similar to the telescopic torque shaft of the cutter chain drive. The upper end of the shaft 57 is mounted within a hollow sleeve 58 journaled in a bearing 59 supported by the adjustable frame member 28, and formed on the upper end of the shaft 57 is a spur pinion 60 meshing with a large internal gear 61 herein formed integral with the swiveled kerf cutter supporting frame 37. It will thus be seen that when the clutch 50 is applied and the clutch 52 is released, the kerf cutter may be swung about its pivot at a slow cutting speed in one direction, and when the clutch 50 is released and the clutch 52 is applied, the kerf cutter may be swung in the opposite direction at a slow speed appropriate for cutting.

Now referring to the improved mechanism for adjusting the kerf cutter into different elevated positions, it will be observed that the shaft 18, as shown in Fig. 3, has formed integral therewith a bevel pinion 62 meshing with reverse bevels 63 and 64, as shown in Fig. 4. The reverse bevels are selectively connectible to a horizontal shaft 65 by multiple disc clutches 66 and 67 respectively. The shaft 65 extends transversely of and is journaled within the cutter frame section 19 and has fixed thereto adjacent its opposite ends and driven thereby worms 68 and 69 meshing with horizontal worm wheels 70 and 71 respectively. These worm wheels have their hubs each journaled in bearing sleeves 72 carried within the cutter frame section, as shown in Fig. 5, and the hubs of these worm wheels are internally threaded at 73 to form adjusting nuts threadedly engaging vertical adjusting screws 74 and 75 respectively. The adjusting screws 74 and 75, as shown in Fig. 5, are keyed at 76 at their upper ends to the adjustable frame member 28 and are threaded at their upper ends at 77 for engagement with a tightening and holding nut 78. It will thus be seen that, depending upon which of the disc clutches 66, 67 is applied, the adjusting nuts may be rotated in one direction or the other to move the adjusting screws 74 and 75 upwardly or downwardly, as desired, and as a result, the adjustable frame member 28 upon which the kerf cutter is swiveled, may be adjusted in a vertical direction relative to the cutter frame section 19 to move the kerf cutter into different horizontal planes. It will be noted that as the adjustable frame supporting the kerf cutter is moved in a vertical direction relative to the cutter frame section 19 the splined shafts 31 and 57 move axially within the shaft 24 and the hub of worm wheel 54, respectively, the shafts sliding freely relative to their cooperative parts as the frame moves.

The means for guiding the adjustable kerf cutter supporting frame 28 during adjustment thereof relative to the cutter frame section 19 herein comprises parallel vertical guide rods 79, 79 each secured at its upper end by a screw and nut connection 80 within a bore 81 formed in a lateral boss 82 integral with the adjustable frame member 28. These parallel guide rods 79 are telescopically arranged and guided within vertically adjustable guide sleeves 83, 83 slidably arranged in vertical bores 84 formed in the cutter frame section 19. Secured transversely within the lower ends of the guide rods are stop pins 85 movable in vertical slots 86 formed in the hollow sleeves 83. After the pins 85 move their distance of travel within the slots 86 and the projecting ends of the pins engage the upper ends of the slots, the sleeves 83 then move with the guide rods, and vertical movement of the sleeves is limited by stop screws 87 having their ends likewise projecting within the vertical slots 86. It will thus be seen that the guide rods 79 and the guide sleeves 83 form a telescopic or extensible guiding arrangement for the adjustable kerf cutter supporting frame 28.

The improved means for controlling the various controlling clutches heretofore described, will now be described. As shown in Fig. 3, engaging the sliding clutch member 26 is a pivoted shipper yoke 88 in the form of a bell crank having an upstanding bifurcated arm 89 engaging a trunnion yoke 90 mounted in a groove 91 formed in an operating rod 92. The rod 92 is rotatably and 75

slidably mounted in a suitable manner within the cutter frame section 19 and extends rearwardly over the top of the machine body as shown in Figs. 1 and 2 and has secured thereto at its forward end an operating handle 93. Splined to the rod 92 at 94 is a shipper yoke 95 engaging a clutch applying member 96 slidably mounted on the shaft 65, as shown in Fig. 4. When the member 96 is slid in one direction or the other, one or the other of the reverse clutches 66, 67 for the elevating mechanism may be applied. It will thus be seen that when the operator grasps the handle 93 and releases a plunger lock 97 from a forward annular groove 98 formed on the rod 92 and shifts the rod 92 axially forwardly from the position of Fig. 2, the shipper yoke 95 is swung about its pivot and the sliding clutch member 26 moved upwardly into its clutched position and the clutch 26 may be held in its clutched position 20 by the plunger lock 97 engaging another rearward groove 98 in the operating rod 92. Of course, reverse axial movement of rod 92 will disengage clutch 26. When it is desired to operate the reverse clutches 66, 67 of the kerf cutter elevating mechanism the handle 93 is turned, thereby rotating the rod 92 and swinging the shipper yoke 95, and as a result the clutch applying member 96 is slid in one direction or the other to apply the desired clutch. The operating means for the reverse frictions 50, 52 for controlling swinging of the kerf cutter herein comprises slid- 30 able clutch shipper members 99, 100 for the clutches 50, 52 respectively, and engaging these clutch shipper members are shipper yokes 101, 102 in the form of bell cranks having laterally projecting arms 103 having bifurcated outer ends 104 straddling the flattened ends 105 of parallel operating rods 106, 107. These rods, as shown in Fig. 6, are pivotally connected at 108 to bell cranks 109 pivotally mounted at 110 on brackets attached to the cutter frame section 19. The inner arms of these bell cranks carry rollers 111 engageable with cam projections 112, 113 formed on a hollow operating rod 114 herein rotatably 40 mounted within a bracket 115 attached to the top of the machine frame and through which the operating rod 92 extends. The forward end of the hollow rod 114 is pivotally connected at 116 to an operating lever 117 pivotally mounted on the top of the machine frame. It will thus be seen that when the lever 117 is swung to move the operating rod 114 forwardly, the cam 112 engages the roller 111 and swings the bell crank 109 about its pivot, thereby moving the rod 106 rearwardly whereupon the shipper yoke 101 is 50 swung about its pivot to apply the disc clutch 50. When the handle 117 is moved in the opposite direction, the clutch 59 is released and the disc clutch 52 is applied by the cam 113, bell crank 109, operating rod 107 and pivoted shipper yoke 102.

In the use of the improved mining machine, the machine is propelled over the mine floor at a high moving speed or at a slow cutting speed 65 by the feed drum 12 and cooperating feed cable 13 in the manner well understood by those skilled in the art. When the machine is suitably positioned adjacent the coal face with the machine frame arranged parallel with and adjacent to the coal face, the kerf cutter is swung about its pivot from the dotted line position shown in Fig. 1 to the full line position, thereby sumping the cutter bar within the coal. When the cutter bar 70 is in the right hand position indicated in full lines in Fig. 1, the bar swing controlling friction

is released and the cutter bar is locked automatically in position by the self-locking bar swinging worm gearing. The machine is then fed bodily along the coal face by the flexible feeding means, thereby cutting a horizontal kerf in the coal. If 5 it is desired to cut a horizontal kerf in the coal at different elevations, the kerf cutter may be adjusted in a vertical direction under the control of the reverse elevating frictions 66, 67. The 10 coacting threads of the adjusting screws and adjusting nuts are self-locking and maintain the cutter bar in any of its adjusted positions. It will thus be seen that the cutter bar may be swung about its pivot under the control of the reverse frictions 50, 52 and that the power operated bar 15 swinging mechanism is operable wholly independently of the flexible feeding means for the machine. It will also be evident that when the cutter bar is in its lowermost position it lies in horizontal planes above the top of the machine frame 20 and is swingable horizontally when in said position completely over the top of the frame. As the mode of operation of a longwall coal mining machine is well known to those skilled in the art, a further description of the mode of operation 25 of the machine is considered unnecessary.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining machine, a machine frame adapted to rest upon and slide in any direction over the mine floor, a horizontal motor carried by said frame and having its power shaft extending longitudinally of said frame, feeding means in said frame and driven from one end of said motor for feeding said frame over the mine floor, kerf cutting mechanism mounted on said frame and driven from the opposite end of said motor, said cutting mechanism including a horizontally swingable kerf cutter, said motor arranged centrally on said frame between said cutting mechanism and said feeding means, means for adjusting the kerf cutter into different elevated positions relative to the frame, said kerf cutter when in its lowermost position lying in horizontal planes above and swingable horizontally completely over the top of said feeding means and the top surface of said motor, and means for swinging said kerf cutter relative to said frame.

2. In a mining machine, a machine frame adapted to rest upon and slide in any direction over the mine floor, a horizontal motor carried by said frame and having its power shaft extending longitudinally of said frame, feeding means in said frame and driven from one end of said motor for feeding said frame over the mine floor, kerf cutting mechanism mounted on said frame and driven from the opposite end of said motor, said cutting mechanism including a horizontally swingable kerf cutter, said motor arranged centrally on said frame between said cutting mechanism and said feeding means, means for adjusting the kerf cutter into different elevated positions relative to the frame, said kerf cutter when in its lowermost position lying in horizontal planes above and swingable horizontally completely over the top of said feeding 75

means and the top surface of said motor, and means operable wholly independently of the feeding means for swinging said kerf cutter relative to said frame.

5. In a mining machine, a machine frame adapted to rest upon and slide in any direction over the mine floor, a horizontal motor carried by said frame and having its power shaft extending longitudinally of said frame, feeding means in said frame and driven from the forward end of said motor for feeding said frame over the mine floor, kerf cutting mechanism mounted on said frame and driven from the rear end of said motor, said cutting mechanism including a horizontally swingable kerf cutter, said motor arranged centrally on said frame between said cutting mechanism and said feeding means, means for adjusting the kerf cutter into different elevated positions relative to the frame, said 10 kerf cutter when in its lowermost position lying in horizontal planes above and swingably horizontally completely over the top of said feeding means and the top surface of said motor, and means for swinging said kerf cutter relative to 15 said frame.

4. In a mining machine, a machine frame adapted to rest upon and slide in any direction over the mine floor, a horizontal motor carried by said frame and having its power shaft extending longitudinally of said frame, feeding means in said frame and driven from the forward end of said motor for feeding said frame over the mine floor, kerf cutting mechanism mounted on said frame and driven from the rear end of said motor, said cutting mechanism including a horizontally swingable kerf cutter, said motor arranged centrally on said frame between said cutting mechanism and said feeding means, means for adjusting the kerf cutter into different elevated positions relative to the frame, said kerf cutter when in its lowermost position lying in horizontal planes above and swingably horizontally completely over the top of said feeding means and the top surface of said motor, and means operable wholly independently of the feeding means for swinging said kerf cutter relative to said frame.

5. In a mining machine, a machine frame adapted to rest upon and slide in any direction over the mine floor, a horizontal motor carried by said frame and having its power shaft extending longitudinally of said frame, feeding means in said frame and driven from one end of said motor for feeding said frame over the mine floor, an adjustable kerf cutting mechanism mounted on said frame and driven from the opposite end of said motor, said cutting mechanism including a horizontal kerf cutter, said motor arranged centrally on said frame between said cutting mechanism and said feeding means, extensible driving connections between said motor and the kerf cutter, and means separate from said extensible driving connections for adjusting said kerf cutter into different elevated positions relative to and above said frame, said kerf cutter when in its lowermost position lying in horizontal planes above said feeding means and the top surface of said motor.

6. In a mining machine, a machine frame adapted to rest upon and slide in any direction over the mine floor, feeding means for the frame, a motor on said frame, an adjustable kerf cutting mechanism mounted on said frame including a horizontal kerf cutter actuated by said motor, and means driven by said motor for adjusting said kerf cutter into different elevated positions

relative to the frame including cooperating relatively rotatable screw and nut elements, said screw elements moving axially upon rotation of said nut elements.

7. In a mining machine, a machine frame adapted to rest upon and slide in any direction over the mine floor, feeding means for the frame, an adjustable kerf cutting mechanism mounted on said frame including a horizontal kerf cutter, means for adjusting said kerf cutter into different elevated positions relative to and above said frame, and means for guiding said kerf cutter during such adjustment, including telescopic guiding elements arranged at opposite sides of said frame.

8. In a mining machine, a frame adapted to rest upon and slide in any direction over the mine floor, a motor on said frame, kerf cutting mechanism thereon including a kerf cutter adjustable into different elevations relative to the frame and actuated by said motor, and means driven by said motor for adjusting said kerf cutter including parallel adjusting screws and cooperating adjusting nuts, said screws being fixed against rotation and moving axially upon adjustment of said kerf cutter.

9. In a mining machine, a frame adapted to rest upon and slide in any direction over the mine floor, a motor on said frame, kerf cutting mechanism on said frame including a kerf cutter adjustable into different elevations relative to the frame and actuated by said motor, and means driven by said motor for adjusting said kerf cutter including parallel adjusting screws and cooperating adjusting nuts, said screws being held against rotation, and means for rotating said nut elements to effect axial movement of said screws.

10. In a mining machine, a frame adapted to rest upon and slide in any direction over the mine floor, a motor on said frame, kerf cutting mechanism on said frame including a kerf cutter adjustable into different elevations relative to the frame and actuated by said motor, means driven by said motor for adjusting said kerf cutter including parallel adjusting screws and cooperating adjusting nuts, said screws being held against rotation, and means for rotating said nuts to effect axial movement of said screws, and means for guiding said kerf cutter during such adjustment.

11. In a mining machine, a frame adapted to rest upon and slide in any direction over the mine floor, kerf cutting mechanism on said frame including a kerf cutter adjustable into different elevations relative to the frame, means for adjusting said kerf cutter including parallel adjusting screws and cooperating adjusting nuts, said screws being held against rotation and adjustable with said kerf cutter, and means for rotating said nuts, and means for guiding said kerf cutter during such adjustment including parallel guide members movable with said kerf cutter.

12. In a mining machine, a frame adapted to rest upon and slide in any direction over the mine floor, kerf cutting mechanism on said frame including a kerf cutter adjustable into different elevations relative to the frame, means for adjusting said kerf cutter including parallel adjusting screws and cooperating adjusting nuts, said screws being held against rotation and adjustable with said kerf cutter and said nuts being stationary as regards bodily movement relative to said frame, means for rotating said nuts, and means for guiding said kerf cutter during such adjustment including parallel guide members.

movable with said kerf cutter and cooperating guiding elements on the frame.

13. In a mining machine, a frame adapted to rest upon and slide in any direction over the mine floor, kerf cutting mechanism on said frame including a kerf cutter adjustable into different elevations relative to the frame, means for adjusting said kerf cutter including parallel adjusting screws and cooperating adjusting nuts, said screws being held against rotation, means for rotating said nuts, and means for guiding said kerf cutter during such adjustment including parallel guide members movable with said kerf cutter and cooperating guiding elements on the frame and movable relative to and guided by said frame.

14. In a mining machine, a machine frame adapted to rest upon and slide in any direction over the mine floor, a horizontal motor having its axis extending longitudinally of said frame, means driven from the forward end of said motor and arranged in said frame for feeding said frame over the mine floor and including a feed member arranged at the forward end of said frame and cooperating flexible feeding means, kerf cutting mechanism driven from the rear end of said motor including a pivoted kerf cutter mounted on the rear end of said frame, said motor arranged centrally on said frame between said cutting mechanism and said feeding means, and means for adjusting said kerf cutter into different elevated positions relative to said frame, said kerf cutter when in its lowermost position lying in horizontal planes above and swingable horizontally completely over the top of said feeding means and the top surface of said motor.

15. In a mining machine, a machine frame adapted to rest upon and slide in any direction over the mine floor, a horizontal motor having its axis extending longitudinally of said frame, means driven from the forward end of said motor and arranged in said frame for feeding said frame over the mine floor and including a feed member arranged at the forward end of said frame and cooperating flexible feeding means, kerf cutting mechanism driven from the rear end of said motor including a pivoted kerf cutter mounted on the rear end of said frame, said motor arranged centrally on said frame between said cutting mechanism and said feeding means, and means for adjusting said kerf cutter into different elevated positions relative to said frame, said kerf cutter when in its lowermost position lying in horizontal planes above and swingable horizontally completely over the top of said feeding means and the top surface of said motor, and means for swinging said kerf cutter about its pivot.

16. In a mining machine, a machine frame adapted to rest upon and slide in any direction over the mine floor, means for feeding said frame over the mine floor during cutting, an adjustable kerf cutting mechanism mounted on said frame including a swingable kerf cutter adjustable into different elevated positions relative to said frame, means for guiding said kerf cutter during such adjustment, and means arranged on said frame in a transverse zone between said kerf cutter pivot and said guiding means for effecting such adjustment of said kerf cutter.

17. In a mining machine, a machine frame adapted to rest upon and slide in any direction over the mine floor, a motor on said frame, means for feeding said frame, kerf cutting mechanism mounted on said frame including a swing-

able kerf cutter actuated by said motor, and means driven by said motor for adjusting said kerf cutter into different elevated positions relative to said frame including parallel adjusting screws movable with said kerf cutter during such adjustment and cooperating adjusting nuts carried within said frame and held stationary as regards bodily movement relative to said frame.

5

18. In a mining machine, a machine frame adapted to rest upon and slide in any direction over the mine floor, a motor on said frame, means for feeding said frame, kerf cutting mechanism mounted on said frame including a swingable kerf cutter actuated by said motor, and means driven by said motor for adjusting said kerf cutter into different elevated positions relative to said frame including parallel adjusting screws movable with said kerf cutter during such adjustment and held against rotation, cooperating adjusting nuts carried within said frame and held stationary as regards bodily movement relative to said frame, and means for rotating said nuts.

10

19. In a mining machine, a machine frame adapted to rest upon and slide in any direction over the mine floor, flexible feeding means for said frame, kerf cutting mechanism mounted on the frame including a horizontally swingable kerf cutter, means for adjusting the elevation of the kerf cutter relative to the frame, and means separate and distinct from said adjusting means for swinging said kerf cutter including a gear attached to the kerf cutter, a pinion meshing with said gear, and motor operated devices for rotating said pinion including a telescopic torque shaft connected to said pinion and a gear element within said frame and relative to which said pinion is adjustable for driving said torque shaft.

25

20. In a mining machine, a machine frame adapted to rest upon and slide in any direction over the mine floor, feeding means for said frame, and an adjustable kerf cutting mechanism mounted on said frame and including a horizontal kerf cutter pivoted for swinging movement, a support on which said kerf cutter is mounted and which is adjustable in a vertical direction to move the kerf cutter into different elevated positions relative to said frame, motor operated devices for actuating said kerf cutter including a kerf cutter driving element and a telescopic torque shaft for rotating said element, and means driven independently of said torque shaft for swinging said kerf cutter.

30

21. In a mining machine, a machine frame adapted to rest upon and slide in any direction over the mine floor, feeding means for said frame, and an adjustable kerf cutting mechanism mounted on said frame and including a horizontal kerf cutter pivoted for swinging movement, a support which carries said kerf cutter and is mounted for bodily adjustment in a vertical direction, a motor carried by said frame, clutch controlled adjusting mechanism operated by said motor to effect aforesaid bodily adjustment of said kerf cutter support, means driven by said motor for actuating said kerf cutter including a kerf cutter driving element and a telescopic torque shaft for rotating said element, and means driven by said motor independently of said torque shaft for swinging said kerf cutter.

55

22. In a mining machine, a machine frame adapted to rest upon and slide in any direction over the mine floor, feeding means for said frame, and an adjustable kerf cutting mechanism mounted on said frame and including a hori-

60

65

70

75

- zontal kerf cutter pivoted for swinging movement, a support which carries said kerf cutter and is mounted for bodily adjustment in a vertical direction, a motor carried by said frame, clutch controlled adjusting mechanism operated by said motor to effect aforesaid bodily adjustment of said kerf cutter support, means driven by said motor for actuating said kerf cutter including a kerf cutter driving element and a telescopic torque shaft for rotating said element, and means driven by said motor for swinging said kerf cutter including a telescopic torque shaft arranged parallel with said first mentioned torque shaft.
23. In a mining machine, a machine frame adapted to rest upon and slide in any direction over the mine floor, feeding means for said frame, a swingable kerf cutter, a support which carries said kerf cutter and is mounted for bodily adjustment in a vertical direction, a motor carried by said frame and relative to which said support is adjustable, driving connections between said motor and said kerf cutter for actuating the latter, and devices driven by said motor for swinging said kerf cutter about its pivot irrespective of the adjusted position of said support including a telescopic torque shaft distinct from said cutter actuating means, gearing carried by said support and driven by said torque shaft and gearing carried within said frame for rotating said torque shaft.
24. In a mining machine, a machine frame adapted to rest upon and slide in any direction over the mine floor, feeding means for said frame, a swingable kerf cutter, a support which pivotally carries said kerf cutter and is mounted for bodily adjustment in a vertical direction, a motor carried by said frame and relative to which said support is adjustable, devices driven by said motor for adjusting said support in aforesaid vertical direction including parallel adjusting screws arranged with their axes in a vertical plane parallel to a transverse vertical plane including the pivotal axis of the kerf cutter, and means for guiding said support during such adjustment including parallel guiding elements arranged with their axes in a vertical plane parallel with and forwardly of aforesaid transverse vertical planes.
25. In a mining machine, a machine frame adapted to rest upon and slide in any direction over the mine floor, feeding means for said frame, a swingable kerf cutter, a support which pivotally carries the kerf cutter and is mounted for bodily adjustment in a vertical direction, a motor carried by said frame and relative to which said support is adjustable, devices driven by said motor for actuating the kerf cutter, and devices driven by said motor for swinging said kerf cutter, each of said devices including a telescopic torque shaft.
26. In a mining machine, a machine frame adapted to rest upon and slide in any direction over the mine floor, feeding means for said frame, a swingable kerf cutter, a support which pivotally carries the kerf cutter and is mounted for bodily adjustment in a vertical direction, a motor carried by said frame and relative to which said support is adjustable, devices driven by said motor for actuating the kerf cutter, and devices driven by said motor for swinging said kerf cutter, each of said devices including a telescopic torque shaft, and each torque shaft including a shaft element journaled on said support, a tubular shaft element journaled within said frame

and within which said first mentioned shaft element is telescopically arranged and a splined connection between said shaft elements.

27. In a mining machine, a machine frame adapted to rest upon and slide in any direction over the mine floor, feeding means for said frame, a swingable kerf cutter, a support which pivotally carries the kerf cutter and is mounted for bodily adjustment in a vertical direction, a motor carried by said frame and relative to which said support is adjustable, devices driven by said motor for actuating the kerf cutter, and devices separate and distinct from said actuating devices and driven by said motor for swinging said kerf cutter, each of said kerf cutter actuating and swinging devices including a terminal driving element journaled on and adjustable with said support.

28. In a mining machine, a machine frame adapted to rest upon and slide in any direction over the mine floor, feeding means for said frame, a swingable kerf cutter, a support which pivotally carries the kerf cutter and is mounted for bodily adjustment in a vertical direction, a motor carried by said frame and relative to which said support is adjustable, devices driven by said motor for actuating the kerf cutter, and devices driven by said motor for swinging said kerf cutter, each of said kerf cutter actuating and swinging devices including a terminal driving element journaled on and adjustable with said support, gearing carried within said frame and a telescopic driving connection between said gearing and said terminal driving element.

29. In a mining machine, a machine frame adapted to rest upon and slide in any direction over the mine floor, feeding means for said frame, a swingable kerf cutter, a support which pivotally carries the kerf cutter and is mounted for bodily adjustment in a vertical direction, a motor carried by said frame and relative to which said support is adjustable, devices driven by said motor for actuating the kerf cutter, and devices driven by said motor for swinging said kerf cutter, each of said devices including a terminal driving element journaled on and adjustable with said support, gearing carried by said frame and a telescopic driving connection between said gearing and said terminal driving element, said telescopic connections each including a shaft element journaled on said support, a tubular shaft element journaled within said frame and within which said first mentioned shaft element is telescopically arranged and a splined connection between said shaft elements.

30. In a mining machine, a machine frame adapted to rest upon and slide in any direction over the mine floor, feeding means for said frame, a swingable kerf cutter, a support which pivotally carries said kerf cutter and is mounted for bodily adjustment in a vertical direction, a motor carried by said frame and relative to which said support is adjustable, devices driven by said motor for actuating said kerf cutter, and devices driven by said motor for swinging said kerf cutter in opposite directions about its pivot including a reversing mechanism carried within said frame and connections between said reversing mechanism and said kerf cutter including a telescopic torque shaft.

31. In a mining machine, a machine frame adapted to rest upon and slide in any direction over the mine floor, feeding means for said frame, a swingable kerf cutter, a support which pivotally carries said kerf cutter and is mounted for bodily adjustment in a vertical direction, a motor car-

- ried by said frame and relative to which said support is adjustable, devices driven by said motor for actuating said kerf cutter, and devices driven by said motor for swinging said kerf cutter in opposite directions about its pivot including a reversing mechanism and a speed reducing transmission mechanism carried within said frame and driven through said reversing mechanism and connections between said speed reducing mechanism and said kerf cutter including a telescopic torque shaft.
32. In a mining machine, a frame adapted to rest upon and slide in any direction over the mine floor, kerf cutting mechanism on said frame including a kerf cutter adjustable into different elevations relative to the frame, means for adjusting said kerf cutter including parallel adjusting screws and cooperating adjusting nuts and means for relatively rotating said screws and nuts, and means for guiding said kerf cutter during such adjustment including parallel guide members movable with said kerf cutter and cooperating guiding elements on the frame and movable relative to and guided by said frame.
33. In a mining machine, a machine frame adapted to rest upon and slide in any direction over the mine floor, feeding means for said frame, a swingable kerf cutter, a support which pivotally carries the kerf cutter and is mounted for bodily adjustment in a vertical direction, a motor carried by said frame and relative to which said support is adjustable, devices driven by said motor for actuating said kerf cutter including a kerf cutter driving element journaled on said support, a gear journaled within said frame and connections including a telescopic torque shaft driven by said gear for rotating said kerf cutter driving element, and devices separate and distinct from said driving element rotating connections and driven by said gear for swinging said kerf cutter.
34. In a mining machine, a machine frame adapted to rest upon and slide in any direction over the mine floor, feeding means for said frame, a swingable kerf cutter, a support which pivotally carries the kerf cutter and is mounted for bodily adjustment in a vertical direction, a motor carried by said frame and relative to which said support is adjustable, devices driven by said motor for actuating said kerf cutter including a kerf cutter driving element journaled on said support, a gear journaled within said frame and connections including a telescopic torque shaft driven by said gear for rotating said kerf cutter driving element, and devices driven by said gear for swinging said kerf cutter about its pivot in opposite directions including a reversing mechanism carried within said frame.
35. In a mining machine, a machine frame adapted to rest upon and slide in any direction over the mine floor, feeding means for said frame, a swingable kerf cutter, a support which pivotally carries the kerf cutter and is mounted for bodily adjustment in a vertical direction, a motor carried by said frame and relative to which said support is adjustable, devices driven by said motor for actuating said kerf cutter including a kerf cutter driving element journaled on said support, a gear journaled within said frame and connections including a torque shaft driven by said gear for rotating said kerf cutter driving element, and devices driven by said gear for swinging said kerf cutter about its pivot in opposite directions including a reversing mechanism and a speed reducing transmission mechanism driven through said reversing mechanism and both mechanisms carried within said frame.
36. In a mining machine, a machine frame adapted to rest upon and slide in any direction over the mine floor, feeding means for said frame, a swingable kerf cutter, a support which pivotally carries the kerf cutter and is mounted for bodily adjustment in a vertical direction, a motor carried by said frame and relative to which said support is adjustable, devices driven by said motor for actuating said kerf cutter including a kerf cutter driving element journaled on said support, a gear journaled within said frame and connections including a telescopic torque shaft driven by said gear for rotating said kerf cutter driving element, and devices driven by said gear for swinging said kerf cutter including a kerf cutter swinging element journaled on said support, a driving element journaled within said frame and connections including a telescopic torque shaft between said kerf cutter swinging element and said driving element.
37. In a mining machine, a machine frame adapted to rest upon and slide in any direction over the mine floor, feeding means in said frame for feeding said frame over the mine floor, kerf cutting mechanism mounted on said frame including a horizontally swingable kerf cutter, means for adjusting the kerf cutter into different elevated positions relative to the frame, said kerf cutter when in its lowermost position lying in horizontal planes above said feeding means and the top surface of said frame and swingable horizontally when in said position completely over the tops of said feeding means and said frame, and means for swinging said kerf cutter relative to said frame.
38. In a mining machine, a machine frame adapted to rest upon and slide in any direction over the mine floor, feeding means in said frame for feeding said frame over the mine floor, kerf cutting mechanism mounted on said frame including a horizontally swingable kerf cutter, means for adjusting the kerf cutter into different elevated positions relative to the frame, said kerf cutter when in its lowermost position lying in horizontal planes above said feeding means and the top surface of said frame and swingable horizontally when in said position completely over the tops of said feeding means and said frame, and means operable wholly independently of the feeding means for swinging said kerf cutter relative to said frame.
39. In a mining machine, a machine frame adapted to rest upon and slide in any direction over the mine floor, a motor carried by said frame, feeding means in said frame for feeding the frame over the mine floor, said feeding means driven by said motor, kerf cutting mechanism mounted on said frame including a horizontally swingable kerf cutter which is driven by said motor, means driven by said motor for adjusting said kerf cutter into different elevated positions relative to the frame, said kerf cutter when in its lowermost position lying in horizontal planes above said feeding means and the top surface of said motor and swingable horizontally when in said position completely over the tops of said feeding means and said motor, and means driven by said motor for swinging said kerf cutter relative to the frame.
40. In a mining machine, a machine frame adapted to rest upon and slide in any direction over the mine floor, a motor carried by said frame, feeding means in said frame for feeding

the frame over the mine floor, said feeding means driven by said motor, kerf cutting mechanism mounted on said frame including a horizontally swingable kerf cutter which is driven by said motor, means driven by said motor for adjusting said kerf cutter into different elevated positions relative to the frame, said kerf cutter when in its lowermost position lying in horizontal planes above said feeding means and the top surface 5 of said motor and swingable horizontally when in said position completely over the tops of said feeding means and said motor, and means operable wholly independently of the feeding means for swinging said kerf cutter relative to the frame.

15 41. In a mining machine, a machine frame adapted to rest upon and slide in any direction over the mine floor, feeding means in said frame for feeding the frame over the mine floor, an adjustable kerf cutting mechanism mounted on 20 said frame including a horizontal kerf cutter, means for adjusting said kerf cutter into different elevated positions relative to and above said frame, said kerf cutter when in its lowermost position lying above said feeding means 25 and the top surface of said frame, and extensible driving connections separate from said adjusting means for driving said kerf cutter.

42. In a mining machine, a machine frame adapted to rest upon and slide in any direction 30 over the mine floor, a kerf cutter mounted on said frame for adjustment into parallel cutting positions and for pivotal movement relative thereto, means for swinging said kerf cutter about its pivot relative to said frame, and means 35 for adjusting said kerf cutter into aforesaid parallel cutting positions relative to said frame, said adjusting means including a motor on said frame and relative to which said kerf cutter is adjustable, a transverse shaft journaled in said frame, 40 a pair of adjusting devices one on each side of said frame, gearing connecting the ends of said shaft with said adjusting devices, respectively, and driving connections between said motor and said transverse shaft.

45 43. In a mining machine, a machine frame adapted to rest upon and slide in any direction over the mine floor, a kerf cutter mounted on 50 said frame for adjustment into parallel cutting positions and for pivotal movement relative thereto, means for swinging said kerf cutter about its pivot relative to said frame, and means 55 for adjusting said kerf cutter into aforesaid parallel cutting positions relative to said frame, said adjusting means including a motor on said frame and relative to which said kerf cutter is adjustable, a transverse shaft journaled in said frame, 60 a pair of adjusting devices one on each side of said frame, gearing connecting the ends of said shaft with said adjusting devices, respectively, and reversible driving connections between said motor and said transverse shaft for driving the latter in either of opposite directions while the motor runs continuously in the same direction.

44. In a mining machine, a machine frame 65 adapted to rest upon the slide in any direction over the mine floor, a kerf cutter mounted on said frame for adjustment into parallel cutting positions and for pivotal movement relative thereto, means for swinging said kerf cutter about its pivot relative to said frame, and means 70 for adjusting said kerf cutter into aforesaid parallel cutting positions relative to said frame, said adjusting means including a motor on said frame and relative to which said kerf cutter is 75 adjustable, a transverse shaft journaled in said

frame, a pair of screw and nut adjusting devices one on each side of said frame, gearing connecting the ends of said shaft with said adjusting devices, respectively, and driving connections between said motor and said transverse shaft.

45. In a mining machine, a machine frame adapted to rest upon and slide in any direction over the mine floor, a kerf cutter mounted on said frame for adjustment into parallel cutting positions and for pivotal movement relative thereto, 10 means for swinging said kerf cutter about its pivot relative to said frame, and means for adjusting said kerf cutter into aforesaid parallel cutting positions relative to said frame, said adjusting means including a motor on said frame and relative to which said kerf cutter is adjustable, a transverse shaft journaled in said frame, 15 a pair of screw and nut adjusting devices one on each side of said frame, gearing connecting the ends of said shaft with said adjusting devices, respectively, 20 and reversible driving connections between said motor and said transverse shaft for driving the latter in either of opposite directions while the motor runs continuously in the same direction.

46. In a mining machine, a machine frame adapted to rest upon and slide in any direction over the mine floor, a kerf cutter mounted on said frame for adjustment into parallel cutting positions and for pivotal movement relative thereto, 30 means for swinging said kerf cutter about its pivot relative to said frame, and means for adjusting said kerf cutter into aforesaid parallel cutting positions relative to said frame, said adjusting means including a motor on said frame and relative to which said kerf cutter is adjustable, a transverse shaft journaled in said frame, 35 a pair of adjusting devices one on each side of said frame, gearing connecting the ends of said shaft with said adjusting devices, respectively, 40 and driving connections between said motor and said transverse shaft, said gearing including worms driven by said shaft one on each end of said shaft, and worm wheels driven by said worms and operatively connected to said adjusting devices.

47. In a mining apparatus, a machine frame adapted to rest upon and slide in any direction over the mine floor, a kerf cutter mounted on said frame for adjustment into parallel cutting positions and for pivotal movement relative thereto, 50 means for adjusting said kerf cutter into aforesaid parallel cutting positions relative to said frame, and means for swinging said kerf cutter about its pivot relative to said frame, said kerf cutter swinging means including a motor on said frame and relative to which said kerf cutter is adjustable, a driving element journaled in said frame, a driven element adjustable with said kerf cutter, extensible driving connections between said driving and driven elements, and reversing driving connections in said frame for connecting said driving element to said motor.

48. In a mining apparatus, a machine frame adapted to rest upon and slide in any direction over the mine floor, a kerf cutter mounted on said frame for adjustment into parallel cutting positions and for pivotal movement relative thereto, means for adjusting said kerf cutter into aforesaid parallel cutting positions relative to said frame, and means for swinging said kerf cutter about its pivot relative to said frame, said kerf cutter swinging means including a motor on said frame and relative to which said kerf cutter is adjustable, a driving element journaled in said frame, a driven element adjustable with said kerf 75

5 cutter, extensible driving connections between said driving and driven elements, and reversing driving connections in said frame for connecting said driving element to said motor, said reversing connections including a transverse shaft, clutch controlled gearing between said shaft and said motor for driving the former in one direction, and clutch controlled gearing between said shaft and said motor for driving the former in the 10 opposite direction.

49. In a mining machine, a machine frame adapted to rest upon and slide in any direction over the mine floor, feeding means for said frame, and an adjustable kerf cutting mechanism 15 mounted on said frame and including a kerf cutter, a support on which said kerf cutter is mounted and which is adjustable in a vertical direction to move the kerf cutter into different elevated positions relative to said frame, motor operated devices for actuating said kerf cutter including a kerf cutter driving element and an extensible shaft connection for rotating said element, and means driven independently of said extensible shaft connection for adjusting said 20 kerf cutter and support in aforesaid vertical direction relative to said frame.

50. In a mining machine, a machine frame adapted to rest upon and slide in any direction over the mine floor, feeding means for said frame, 30 and an adjustable kerf cutting mechanism mounted on said frame including a horizontal kerf cutter, a support which carries said kerf cutter and is mounted for bodily adjustment in a vertical direction relative to said frame, a motor carried by said frame and relative to which said kerf cutter support is adjustable, means driven by said motor for actuating said kerf cutter including a kerf cutter driving element and an extensible shaft connection for rotating said element, and clutch controlled adjusting mechanism operated by said motor independently of said extensible shaft connection to effect aforesaid bodily adjustment of said kerf cutter support.

45 51. In a mining machine, a machine frame adapted to rest upon and slide in any direction over the mine floor, feeding means for said frame, and an adjustable kerf cutting mechanism mounted on said frame including a horizontal 50 kerf cutter pivoted for swinging movement, a support which carries said kerf cutter and is mounted for bodily adjustment in a vertical direction relative to said frame, a motor carried by said frame and relative to which said kerf cutter support is adjustable, means driven by said motor for actuating said kerf cutter including a kerf cutter driving element and an extensible shaft connection for rotating said element, clutch controlled adjusting mechanism operated by said 55 motor independently of said extensible shaft connection to effect aforesaid bodily adjustment of said kerf cutter support, and means driven by said motor for swinging said kerf cutter including an extensible shaft connection separate from said 60 extensible shaft connection.

52. In a mining machine, an elongated machine frame adapted to rest upon and slide in any direction over the mine floor, feeding means for 70 said frame, a kerf cutter projecting from one end of said machine, a support which carries said kerf cutter and is mounted for bodily adjustment in a vertical direction relative to said machine frame, a motor carried by said frame and relative to which said support is adjustable, devices driven by 75 said motor for adjusting said support in afore-

said vertical direction including parallel adjusting screws arranged with their axes in a vertical plane parallel to a vertical plane transverse to the machine frame and intersecting the kerf cutter, and means for guiding said support during such adjustment including parallel guiding elements arranged with their axes in a vertical plane parallel with aforesaid transverse vertical planes and nearer the end of the frame from which the kerf cutter does not project than said 10 planes.

53. In a mining machine, a machine frame adapted to rest upon and slide in any direction over the mine floor, feeding means for said frame, a kerf cutter, a support which carries the 15 kerf cutter and is mounted for bodily adjustment in a vertical direction relative to said frame, a motor carried by said frame and relative to which said support is adjustable, devices driven by said motor for actuating said kerf cutter including a kerf cutter driving element journaled on said support, a gear journaled within said frame and an extensible driving connection driven by said gear for rotating said kerf cutter driving element irrespective of the adjusted position of said 20 support relative to said frame, and devices separate and distinct from said extensible driving connection and driven by said gear for bodily adjusting said kerf cutter support in aforesaid vertical direction.

54. In a mining machine, a machine frame adapted to rest upon and slide in any direction over the mine floor, feeding means for said frame, a kerf cutter, a support which carries the kerf cutter and is mounted for bodily adjustment in 30 a vertical direction relative to said frame, a motor carried by said frame and relative to which said support is adjustable, devices driven by said motor for actuating said kerf cutter including a kerf cutter driving element journaled on said support, a gear journaled within said frame and connections including an extensible driving connection driven by said gear for rotating said kerf cutter driving element, and devices driven by 40 said gear for bodily adjusting said kerf cutter support in aforesaid vertical direction relative to said frame and including adjusting devices driven by said motor independently of said extensible driving connection.

55. In a mining machine, a machine frame 50 adapted to rest upon and slide in any direction over the mine floor, a kerf cutter mounted on said frame for adjustment into parallel cutting positions, and means for adjusting said kerf cutter into aforesaid parallel cutting positions relative to said frame, said adjusting means including a motor on said frame and relative to which said kerf cutter is adjustable, a transverse shaft journaled in said frame, a pair of 55 adjusting devices one on each side of said frame, gearing connecting the ends of said shaft with said adjusting devices, respectively, and driving connections between said motor and said transverse shaft.

56. In a mining machine, a machine frame 65 adapted to rest upon and slide in any direction over the mine floor, a kerf cutter mounted on said frame for adjustment into parallel cutting positions, and means for adjusting said kerf cutter into aforesaid parallel cutting positions 70 relative to said frame, said adjusting means including a motor on said frame and relative to which said kerf cutter is adjustable, a transverse shaft journaled in said frame, a pair of 75 adjusting devices one on each side of said frame,

gearing connecting the ends of said shaft with said adjusting devices, respectively, and reversible driving connections between said motor and said transverse shaft for driving the latter in either 5 of opposite directions while the motor runs continuously in the same direction.

57. In a mining machine, a machine frame adapted to rest upon and slide in any direction over the mine floor, a kerf cutter mounted on 10 said frame for adjustment into parallel cutting positions, and means for adjusting said kerf cutter into aforesaid parallel cutting positions relative to said frame, said adjusting means including a motor on said frame and relative to which 15 said kerf cutter is adjustable, a transverse shaft journaled in said frame, a pair of screw and nut adjusting devices one on each side of said frame, gearing connecting the ends of said shaft with said adjusting devices, respectively, and 20 driving connections between said motor and said transverse shaft.

58. In a mining machine, a machine frame adapted to rest upon and slide in any direction over the mine floor, a kerf cutter mounted on 25 said frame for adjustment into parallel cutting positions, and means for adjusting said kerf cutter into aforesaid parallel cutting positions relative to said frame, said adjusting means including a motor on said frame and relative to which 30 said kerf cutter is adjustable, a transverse shaft journaled in said frame, a pair of screw and nut adjusting devices one on each side of said frame, gearing connecting the ends of said shaft with said adjusting devices, respectively, and 35 reversible driving connections between said motor and said transverse shaft for driving the latter in either of opposite directions while the motor runs continuously in the same direction.

59. In a mining machine, a machine frame 40 adapted to rest upon and slide in any direction over the mine floor, a kerf cutter mounted on said frame for adjustment into parallel cutting positions, and means for adjusting said kerf cutter into aforesaid parallel cutting positions relative to said frame, said adjusting means in- 45

cluding a motor on said frame and relative to which said kerf cutter is adjustable, a transverse shaft journaled in said frame, a pair of adjusting devices one on each side of said frame, gearing connecting the ends of said shaft with 5 said adjusting devices, respectively, and driving connections between said motor and said transverse shaft, said gearings including worms driven by said shaft one on each end of said shaft, and worm wheels driven by said worms 10 and operatively connected to said adjusting devices.

60. In a mining apparatus, a machine frame adapted to rest upon and slide in any direction over the mine floor, a kerf cutter mounted on 15 said frame for adjustment into parallel cutting positions, means for adjusting said kerf cutter into aforesaid parallel cutting positions relative to said frame, said kerf cutter adjusting means including a motor on said frame and relative to which said kerf cutter is adjustable and reversible driving connections in said frame, and 20 kerf cutter driving means actuated by said motor including a driving element journaled in said frame, a driven element adjustable with said kerf 25 cutter and extensible driving connections between said driving and driven elements.

61. In a mining machine, a machine frame adapted to rest upon and slide in any direction over the mine floor, feeding means for said frame, 30 a kerf cutter, a support which carries said kerf cutter and is mounted for bodily adjustment in a vertical direction relative to said frame, a motor carried by said frame and relative to which said support is adjustable, devices driven by said motor for actuating said kerf cutter including a kerf cutter driving element journaled on said support, a gear journaled within said frame and extensible driving connections between said gear and said driving element, and 35 means separate and distinct from said extensible driving connection for bodily adjusting said support in aforesaid vertical direction relative to said frame.

MORRIS P. HOLMES. 45

CERTIFICATE OF CORRECTION.

Patent No. 1,996,766.

April 9, 1935.

MORRIS P. HOLMES.

It is hereby certified that error appears in the printed specification of the above numbered patent requiring correction as follows: Page 1, second column, line 23, the semi-colon should be a comma; and line 25, the comma should be a semi-colon; page 4, first column, line 21, claim 3, for "swingably" read swingable; page 5, second column, line 34, claim 19, after "gear" strike out the comma; and page 8, first column, line 65, claim 44, for "the" read and; and that the said Letters Patent should be read with these corrections therein that the same may conform to the record of the case in the Patent Office.

Signed and sealed this 18th day of June, A. D. 1935.

Leslie Frazer
